UNITED STATES PATENT OFFICE.

EDWIN A. ROONEY, OF FAIRHAVEN, MASSACHUSETTS, ASSIGNOR TO THE WHITIN MACHINE WORKS, OF WHITINSVILLE, MASSACHUSETTS, A CORPORATION OF MASSACHUSETTS.

SCAVENGER-BRUSH FOR COMBERS.

1,258,709.

Specification of Letters Patent. Patented Mar. 12, 1918.

Application filed August 10, 1914. Serial No. 855,967.

To all whom it may concern:

Be it known that I, EDWIN A. ROONEY, a citizen of the United States, residing at Fairhaven, in the county of Bristol and State 5 of Massachusetts, have invented the following-described new and useful Improvements in Scavenger-Brushes for Combers.

The invention concerns the manner of attachment to their shaft of the cylindrical 10 brushes which scavenge the combing cylinders of Heilmann type combers. In such machines the combing cylinders are mounted on the common comb shaft, journaled in a series of intermediate frame uprights, one 15 between each pair of cylinders, and the rotary brushes for such cylinders are similarly mounted on a common brush shaft, also journaled in the same uprights between each pair of adjacent brushes. As the brushes 20 become worn out, new ones have to be secured to the shaft, and it is desirable that the brushes be removable without requiring the shaft to be withdrawn from its set of journal boxes in the uprights. The present 25 invention provides a brush mounting whereby the brush stock, divided into two parts or halves, can be clamped around the shaft, between bearings, and fixedly secured thereto, and whereby it can be easily removed and 30 replaced when necessary. The invention also concerns the structure of the brush itself, whereby its useful life is prolonged and replacements rendered necessary only at infrequent intervals, all as will be herein- 35 after fully set forth and claimed.

In the drawings forming part hereof,

Figure 1 is an elevation of a comber brush and part of the next adjacent brush, showing the bearing for the brush shaft and also 40 a portion of a comb cylinder in section;

Fig. 2 is an end elevation of the brush, partly in section; and

Fig. 3 is a side elevation of the end of a brush, partly in section.

45 In Fig. 1 the combing cylinder is marked 1, its shaft 2, the brush shaft 3, and the intermediate frame upright 4. The shafts 2 and 3 are both journaled in the upright 4, and it will be understood, as above stated, 50 that there is a similar upright at each end of each brush and cylinder in the comber.

The scavenger brush is formed of two semi-cylindrical brush stocks 5, each equipped

with radial bristles, which for the present may be assumed to be of ordinary vegetable 55 fiber such as common to use for this purpose. The stocks are each provided with semi-cylindrical grooves on their proximate faces, adapted to fit upon and around the brush shaft 3. Each brush stock is ordinarily and 60 conveniently made of wood and is circumferentially rabbeted at each end and shod with a semi-circular metal end or shoe 6, which fits and fills the wooden rabbet, projecting beyond the wood as a virtual extension of the stock itself. The shoes 6 are fastened to the stock in any secure manner, as by means of one or more wood screws, indicated at 7. Each shoe is also circumferentially rabbeted so that when the two brush 70 stocks are placed around the shaft 3, a substantially continuous circular rabbet-groove will be thereby formed to receive and serve as a seat for the locking-ring 8. These rings 75 8 encircle the brush shaft and are placed thereon when the said shaft is first installed in the comber, two being left between each pair of uprights. The width of the rings is such that when one is placed adjacent to each brush shaft journal (9 in Fig. 1) there will 80 yet be space enough between them in which to place the two brush stocks upon the shaft, so that the rings can be slipped into the annular seat on the shoes 6. From the dotted-line representations in Fig. 1, it will be observed that the rings may even be moved 85 over the ends of the journal-box 9, if necessary, while the brush is being assembled, thus allowing a maximum length of shaft upon which to adjust the position of the 90 brush, and also a maximum length of brush. When the two rings 8 have been seated on the metal shoes, the three radial screws 10 in the latter are set up to force the halves of the brush together and clamp them fast 95 upon the shaft. Sufficient clearance is allowed between the wooden faces of the stocks to allow them to be so tightened, and also to be further tightened if after a period of use they become loose. When the brush is 100 worn out, it is removed by unscrewing the same screws and slipping the rings off the ends of the rabbeted shoes, as will be evident, and it will be noted that there are no parts to hamper the free use of the screw-driver or 105 wrench used in the operations of assembling

or disassembling the brush, since the screws 10 are accessible on the outer or peripheral faces of the rings.

The bristles 11 are preferably made of 5 vegetable fiber, as above stated, and wear thereof is retarded by incorporating in them a series or row of metallic bristles 12, one of such series or rows being desirably applied at about the middle of each half brush stock 10 and extending the full length of the other rows of bristles. These metallic bristles are fine steel wires mounted in card clothing 12^a 15 tacked to the brush, and each wire is spaced from the others so that it possesses the full degree of resilience resulting from its fineness and length. The gentle rubbing of these hard, but yielding, steel wires upon the needles of the combing cylinders appears to 20 keep them brightly polished without any scoring or scratching, so that wear of the vegetable bristles takes place at a slower rate than would otherwise be the case, and the life of the brush as a whole is prolonged. The metallic bristles even when spaced from 25 each other, however, are slightly stiffer than the vegetable bristles and can therefore remove bunches of cotton from the combing cylinder which the other bristles alone could not pick up, the result of which is to keep 30 the cylinder and the sliver produced thereby in a cleaner condition than is otherwise possible. It will be understood that the brush and cylinder are so rotated that the combing needles on the latter pass through the bristles of the brush in the direction to wipe 35 the dirt off the points of the needles, the latter being inclined as usual. This relationship of the parts avoids dulling the needle points by contact with the metal bristles,

notwithstanding the traverse motion usually 40 imparted to the brush shaft.

I am aware that steel wire bristles have heretofore been used in brushes for textile and other purposes, but I believe myself to be the first to have utilized the combination 45 of a few of such bristles with the regular vegetable or organic bristles in operation upon a combing cylinder, whereby the life of the brush is prolonged and the comb cylinder and the lap combed thereby are made 50 cleaner.

I claim:

1. The combination in a comber, of a comb cylinder and a rotary scavenger brush co-acting therewith comprising a group of vegetable or organic bristles and a row of slender 55 or yielding metallic bristles.

2. The combination in a comber, of a comb cylinder and a rotary scavenger brush co-acting therewith, comprising a relatively 60 wide group of vegetable or organic bristles and a relatively narrow row of slender metallic bristles.

3. A scavenger brush construction for combers comprising in combination with the 65 comb cylinder, a rotary scavenger brush composed of assembled brush stocks, each stock carrying several rows of vegetable or organic brush bristles and a less number of 70 rows of elastic, slender, wire bristles adapted for engagement with the comb cylinder.

In testimony whereof, I have signed this specification in the presence of two witnesses.

EDWIN A. ROONEY.
